UNITED STATES PATENT OFFICE.

JOHN MITCHELL, OF NORTHAMPTON, PENNSYLVANIA.

CORSET-FASTENER.

1,224,486.

Specification of Letters Patent.

Patented May 1, 1917.

Application filed October 25, 1916. Serial No. 127,636.

To all whom it may concern:

Be it known that I, JOHN MITCHELL, a citizen of the United States, residing at Northampton, in the county of Northampton and State of Pennsylvania, have invented 5 a new and useful Corset-Fastener, of which the following is a specification.

It is the object of this invention to provide novel means whereby, without using a lacing 10 cord, an adjustable, step by step connection between the front portions of a corset may be afforded.

In the accompanying drawings:—

Figure 1 shows in front elevation, a portion 15 of a corset whereunto the device forming the subject matter of this application has been applied, parts being broken away;

Fig. 2 is a top plan of a hook which constitutes one member of the separable connector or fastener forming the subject matter 20 of this application;

Fig. 3 is a side elevation of the hook shown in Fig. 2.

In Fig. 1 of the drawings, one edge of the 25 corset, at the front, is denoted by the numeral 14 and carries a stay 15. Held to the stay 15 by means of rivets 17 is an eye 16 connected with one end of a chain 18. The opposite edge of the corset is denoted by the 30 numeral 19 and carries a stay 20. The de-

vice comprises a hook including base arms 21 having eyes 22 united by rivets 23 with the stay 20. The base arms 21 of the hook terminate in outstanding arms 24 merging into back bent fingers 25 connected by a cross bar 35 26. Any link of the chain 18 may be engaged between the parts 24—25 at the opposite sides of the hook, and thus a step by step adjustment between the edges 14 and 19 of the corset may be brought about. 40

Having thus described the invention, what is claimed is:—

In a separable fastener, a hook including base members having eyes, the base members terminating in outstanding arms merging into back-bent fingers extended toward the base members and connected by a cross bar disposed transversely of the base members and supported thereon; and a flexible element engaged between the arms and the 50 fingers and supported on the cross bar, the flexible element having a projection coacting with the fingers. 45

In testimony that I claim the foregoing as my own, I have hereto affixed my signature in the presence of two witnesses. 55

JOHN MITCHELL.
